UNITED STATES PATENT OFFICE.

GEORGE C. MURRAY, OF CHICAGO, ILLINOIS, ASSIGNOR TO KEYOKE RAILWAY EQUIPMENT COMPANY, A CORPORATION OF DELAWARE.

DRAFT-GEAR.

1,175,549.

Specification of Letters Patent. Patented Mar. 14, 1916.

Application filed May 23, 1912. Serial No. 699,188.

To all whom it may concern:

Be it known that I, GEORGE C. MURRAY, a citizen of the United States, residing at Chicago, in the county of Cook and State 5 of Illinois, have invented certain new and useful Improvements in Draft-Gear, of which the following is a specification.

The object of my invention is to provide improved means for connecting the yoke 10 used in connection with draft gears of railway rolling stock with the draw-bar which carries the coupler. The most common means heretofore used for forming the connection referred to has been by the use of 15 rivets passing through the outer ends of the yoke and the inner end of the draw-bar.

It is one of the purposes of my invention 20 to do away with the disadvantages inherent in the use of rivets and other forms of connection heretofore used.

The precise object and nature of my invention will more clearly appear from the following description and claims, taken in connection with the drawings in which—

25 Figure 1 is a perspective view with part of the structure broken away. Fig. 2 is a fragmentary view showing several of the parts going to make up my improved structure, the parts being separated but occupying approximately their proper relative positions, and spaced apart sufficiently to show the form of the different elements. Fig. 2^a is a view showing a detail modification. Fig. 3 is a longitudinal central vertical section 30 through the end of the draw-bar and yoke. Fig. 4 is a transverse section upon a vertical plane passing through the keys by which various members are held together. Fig. 5 is a longitudinal cross section showing 35 my invention applied to a different form of draw-bar.

In the drawings, I have illustrated, for 40 purposes of explanation, one specific form of structure in which my invention may be embodied. It will be understood, however, that my invention is applicable without adherence to the specific structural forms 45 herein shown and illustrated, and that the relation of the various parts may be quite 50 widely changed without departing from my invention.

The draw-bar 1 carries at its outer end 55 the usual coupler-head 2 and at its inner end is provided with an enlarged head 3, at the outer end of which head there are

shoulders 4 to be engaged by the outer ends of the yoke. In Fig. 1 the draw-bar and yoke are illustrated in connection with one of the draft sills 7, the other draft sill being omitted to more plainly exhibit the 60 structure. The draft sill 7 is provided with the usual stops 8 and 9 and within the yoke I have shown a draft spring 10 having at its ends followers 11, 12, which are adapted to coact with the stops 8 and 9. It will be 65 obvious that any form of draft rigging may be used in connection with my invention, that illustrated being shown merely for the purpose of illustrating a common arrangement of these parts.

The outer ends of the yoke 5 are provided with inturned lugs 14, 15 adapted to engage the shoulders 4 upon the draw-bar. In order to hold the lugs 14, 15 of the yoke in engagement with the shoulders upon the 70 draw-bar, I provide a clamp designated generally by the numeral 16. According to my present invention I construct the clamp 75 16 in two parts designated by the numerals 17 and 18. The upper clamp member 17 80 comprises a top plate 19 having depending ears 20, the top clamp member 17 being adapted to surround the top and sides of the engaging parts of the yoke and draw-bar. The lower clamp member 18 extends 85 between the ears 20 beneath the yoke and draw-bar and consists of a bottom plate 21 having at its sides depending ears 22 and a lug 27 to hold clamp shoulders against 90 yoke shoulders.

The depending ears 20 of the top yoke member are provided with key openings 23 and key openings 24 are provided in the depending ears 22 of the lower clamp member. When assembled, as shown in Fig. 1, 95 the upper and lower clamp members are held together by means of a key 25 passing through the key openings 23 and 24. The lower clamp member 18 is also provided with a transverse lug or flange 40 against 100 which the key 25 bears, thus holding the lug 27 of the lower clamp member 18 against the lugs 14, 15 of the yoke members.

It is advantageous to construct the clamp 16 in two separable members for the reason 105 that it facilitates assemblage of the parts and for the further reason that when so constructed the clamp may be provided with ears 26 and 27 upon its upper and lower members respectively, such ears having suf- 110

ficient depth to extend inwardly to the shank of the draw-bar outside of the lugs 14, 15 upon the ends of the yoke. If constructed integrally the lugs or shoulders 26 and 27 5 upon the clamp 16 cannot extend inwardly farther than the outer surface of the head of the draw-bar on account of the impossibility of assembling a structure so made.

While not in all cases necessary, I prefer 10 to key the depending ears 20 of the upper clamp member 19 directly to the draw-bar as illustrated. For this purpose I have shown key openings 29 in the depending ears 20 of the upper clamp member and a key opening 30 extending through the draw-bar. When assembled a key 31 extends through the depending or side ears 20 of the upper clamp member and through the draw-bar; this key preferably also extending 15 outwardly through slots 32 in the draft sills. The keys 25 and 31 may both be secured in position by means of cotter-pins 33.

The key 25 is sufficient in itself to hold 20 the clamp members together, thus securing 25 the inturned lugs 14, 15 of the yoke in operative engagement with the shoulders 4 upon the draw-bar. In the absence of further securing means, however, the clamp might, under some circumstances, become 30 dislodged from its position and move outwardly relative to a draw-bar of the construction shown in Figs. 1 to 4, thus releasing the inner ends of the yoke, and upon buffing stresses the head of the draw-bar without 35 moving the yoke inwardly. While such compression of the draft spring and inward movement of the head of the draw-bar without moving the yoke might not be a serious detriment 40 to the action of the device, it is preferable that the yoke be carried inwardly with the draw-bar when the draft rigging is compressed by buffing stresses. For these reasons I prefer to use the key 31 passing 45 through the depending ears 20 of the upper clamp member and through the draw-bar. An additional advantage secured by the use 50 of the key 31 lies in the fact that it passes through slots 32 in the draft sills and affords means for moving a car when the draft rigging is broken or disabled. Under such circumstances the car may be moved by the transmission of force directly from the draw-bar through the key 31 to the ends of the 55 slots 32 in the draft sills.

It will be seen that the yoke 5 can be displaced laterally when it is desired to disengage its lugs 14 and 15 from the shoulders 4, or when it is desired to assemble these 60 parts in their normal operative relation. It will also be seen that if desired the yoke can be hinged as indicated at 6 in Fig. 2^a.

In Fig. 5 I show a draw-bar 50 having recesses 51 in which the lugs 52 of the yoke 65 and the lugs 53 of the clamp are received.

In this construction the key passing through the yoke and draw-bar may be dispensed with as the key 54 passing through the upper and lower clamp members 55, 56 will, in conjunction with the recesses 51 and lugs 70 52 and 53, securely hold the parts together.

I claim:

1. In a device of the class described, a draw-bar having a shouldered butt, a yoke having lugs at its outer ends adapted to fit 75 over and engage the shoulders of said butt, a clamp surrounding the engaging parts of said yoke and draw-bar, said clamp comprising two members, and means engaging said clamp members to hold them in operative 80 engagement with said yoke and draw-bar and thereby maintain said draw-bar and strap in assembled relation.

2. In a device of the class described, a draw-bar having shoulders near its inner 85 end, a yoke having lugs at its outer ends adapted to engage said shoulders, a clamp surrounding the engaging parts of said draw-bar and yoke, said clamp comprising two members, said members being arranged 90 for assembly to surround the engaging parts of said yoke and draw-bar, and a key extending through openings in said clamp members when in assembled relation to hold them in operative engagement with said 95 yoke and draw-bar.

3. In a device of the class described, a draw-bar having shoulders near its inner end, a yoke having lugs at its outer ends adapted to engage said shoulders, a clamp 100 surrounding the engaging parts of said draw-bar and yoke, said clamp comprising two members, said members being arranged for assembly to surround the engaging parts of said yoke and draw-bar, a key extending 105 through openings in said clamp members when in assembled relation to hold them in operative engagement with said yoke and draw-bar, and a second key extending through one of said clamp members and 110 through said draw-bar.

4. In a device of the class described, a draw-bar having shoulders near its inner end, a yoke having inturned lugs at its ends 115 engaging said shoulders, a clamp surrounding the engaging parts of said yoke and draw-bar, said clamp consisting of upper and lower separable members, said clamp members having inturned lips adapted to overlie the inturned lugs on said yoke, and means for securing said upper and lower 120 clamp members together.

5. In a device of the class described, a draw-bar having shoulders near its inner end, a yoke having inturned lugs at its outer 125 ends engaging said shoulders, a clamp surrounding the engaging parts of said yoke and draw-bar, said clamp consisting of upper and lower members, said upper clamp member embracing the top and sides of said 130

draw-bar and yoke and said lower clamp member extending across the bottom thereof, and a key extending through said upper and lower clamp members and maintaining the same in assembled relation.

6. In a device of the class described, a draw-bar having shoulders near its inner end, a yoke having inturned lugs at its outer ends engaging said shoulders, a clamp 10 surrounding the engaging parts of said yoke and draw-bar, said clamp consisting of upper and lower members, said upper clamp member comprising a top plate and depending ears, said lower clamp member lying between said depending ears below said draw-bar and yoke, and a key extending through said upper and lower clamp members and maintaining the same in assembled relation.

7. In a device of the class described, a draw-bar having shoulders near its inner end, a yoke having inturned lugs at its outer ends engaging said shoulders, a clamp surrounding the engaging parts of said yoke and draw-bar, said clamp consisting of upper and lower members, said upper clamp member comprising a top plate and depend-

ing ears, said lower clamp member lying between said depending ears below said draw-bar and yoke, a key extending through said upper and lower clamp members, and a second key extending through said depending ears and said draw-bar.

8. In a device of the class described, a yoke strap, a draw bar adapted to be seated therein by movement transversely of said strap, a hollow head adapted to be subsequently assembled with the conjoined strap and draw bar, and locking means penetrating but one of said elements to lock all of them in operative conjunction.

9. In a device of the class described, a yoke strap, a draw bar seated therein by movement transversely thereof, a separately formed hollow head slidable longitudinally 45 of the strap, and a locking key interposed between said strap and a part of said hollow head.

In testimony whereof, I have subscribed my name.

GEORGE C. MURRAY.
